C. A. Warner,

Bedstead Cording,

№ 20,750.

Patented June 29, 1858

UNITED STATES PATENT OFFICE.

C. A. WARNER, OF BRISTOL, CONNECTICUT.

BEDSTEAD.

Specification of Letters Patent No. 20,750, dated June 29, 1858.

To all whom it may concern:

Be it known that I, C. A. WARNER, of Bristol, county of Hartford, and State of Connecticut, have invented a new and useful

5 Improvement in Mode of Cording Bedsteads; and I do hereby declare that the same is described and represented in the following specification and drawings, and to enable others skilled in the art to make and
10 use the same I will proceed to describe the construction and operation, referring to the drawings, in which the same letters indicate like parts in each of the figures.

The nature of my improvement consists
15 in the mode of constructing and arranging staples or pins with pulleys thereon placed at regular intervals, over which the cord is placed, one end of which is secured at or near one corner of the bedstead, and the
20 other to a winding spindle having a ratchet and pawl screwed thereto so that the cord may be tightened at will without removing the bedding.

In the accompanying drawings is shown
25 the mode of arranging my improvement.

A, is the bedstead frame; B, the pulleys over which the cord is placed.

C are staples one end of which is bent up so as to allow the pulleys B to be put
30 thereon and headed sufficient to secure it from losing off and having a screw cut on the other end for the purpose of screwing into the slides of the rails to prevent pulling out.

35 D, are pins on each one of which is placed one of the pulleys B, and headed sufficiently to prevent the pulleys from losing off, and are placed at regular intervals in the recess or groove on the upper side and inner edge
40 of the rails E, and in number more or less as may be required.

F, is a spindle for winding up and tightening the cord.

G, is ratchet wheel secured to the winding spindle.

45 H, is a pawl secured to the rail and resting on the teeth of the ratchet wheel.

The cord is first made fast at or near one corner of the bedstead, and laid over the pulleys in regular order until the other end is brought to the winding spindle F, and secured thereto, so that as the spindle is turned the cord is drawn over the pulleys until sufficient tautness is secured to the cord and whenever the cord becomes slack 50 it can easily and readily be tightened by the use of a small lever inserted into one of the holes in the winding spindle made for that purpose.

The present mode of tightening bed cords 55 is very unpleasant and always requires two to perform the work, and is attended with more difficulty in detaching the cord when necessary to take down the bedstead, especially in case of fire, &c. The advantage 60 therefore to be derived from this improvement over others now in use must be at once apparent.

I do not claim either of the parts separately considered as I know they have been 65 in use. But

What I claim and desire to secure by Letters Patent, is—

The arrangement of the staples and pins C, D, pulleys B, spindle F, ratchet G, pawl 70 H, in the manner and for the purpose as described.

C. A. WARNER. [L. s.]
